(57) **CLAIM**

The ornamental design for a root puller as shown and described.

DESCRIPTION

FIG. 1 is a perspective view of a root puller showing the new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view taken from the encircled area 9 in FIG. 1;

FIG. 10 is an enlarged detail view taken from the encircled area 10 in FIG. 1;

FIG. 11 is an enlarged detail view taken from the encircled area 11 in FIG. 1;

FIG. 12 is an enlarged detail view taken from the encircled area 12 in FIG. 1;

FIG. 13 is an enlarged detail view taken from the encircled area 13 in FIG. 1;

FIG. 14 is an enlarged detail view taken from the encircled area 14 in FIG. 1;

FIG. 15 is an enlarged detail view taken from the encircled area 15 in FIG. 2;

FIG. 16 is an enlarged detail view taken from the encircled area 16 in FIG. 2;

FIG. 17 is an enlarged detail view taken from the encircled area 17 in FIG. 2;

FIG. 18 is an enlarged detail view taken from the encircled area 18 in FIG. 2;

FIG. 19 is an enlarged detail view taken from the encircled area 19 in FIG. 2;

FIG. 20 is an enlarged detail view taken from the encircled area 20 in FIG. 2;

FIG. 21 is an enlarged detail view taken from the encircled area 21 in FIG. 3;

FIG. 22 is an enlarged detail view taken from the encircled area 22 in FIG. 3;

FIG. 23 is an enlarged detail view taken from the encircled area 23 in FIG. 3;

FIG. 24 is an enlarged detail view taken from the encircled area 24 in FIG. 3;

(Continued)

FIG. 25 is an enlarged detail view taken from the encircled area 25 in FIG. 4;
 FIG. 26 is an enlarged detail view taken from the encircled area 26 in FIG. 4;
 FIG. 27 is an enlarged detail view taken from the encircled area 27 in FIG. 4;
 FIG. 28 is an enlarged detail view taken from the encircled area 28 in FIG. 4;
 FIG. 29 is an enlarged detail view taken from the encircled area 29 in FIG. 5;
 FIG. 30 is an enlarged detail view taken from the encircled area 30 in FIG. 5;
 FIG. 31 is an enlarged detail view taken from the encircled area 31 in FIG. 5;
 FIG. 32 is an enlarged detail view taken from the encircled area 32 in FIG. 6;
 FIG. 33 is an enlarged detail view taken from the encircled area 33 in FIG. 6;
 FIG. 34 is an enlarged detail view taken from the encircled area 34 in FIG. 6;
 FIG. 35 is an enlarged detail view taken from the encircled area 35 in FIG. 7;
 FIG. 36 is an enlarged detail view taken from the encircled area 36 in FIG. 7;
 FIG. 37 is an enlarged detail view taken from the encircled area 37 in FIG. 7;
 FIG. 38 is an enlarged detail view taken from the encircled area 38 in FIG. 8; and,
 FIG. 39 is an enlarged detail view taken from the encircled area 39 in FIG. 8.

The broken lines shown in the figures are for the purpose of illustrating portions of the root puller and form no part of the claimed design.
